UNITED STATES PATENT OFFICE.

ALLEN W. BODELL, OF WILMETTE, ILLINOIS.

COMBINATION-ENGINE.

1,333,749.

Specification of Letters Patent. Patented Mar. 16, 1920.

Application filed August 15, 1919. Serial No. 317,709.

To all whom it may concern:

Be it known that I, ALLEN W. BODELL, a citizen of the United States, residing at Wilmette, in the county of Cook and State 5 of Illinois, have invented a new and useful Improvement in Combination-Engines, of which the following is a specification.

My invention relates to an improved form of combination engine in which a rotor and one or more reciprocating pistons are operated simultaneously by the action 10 of the same gases under pressure. More specifically my invention consists of providing an engine of this kind with a single 15 mechanism for controlling the operation of the rotor which is acted upon successively by the gases under pressure operating the several pistons of the reciprocatory portion of the engine. While my invention is 20 shown and described as embodied in an internal combustion engine, it will be understood that the same mode of operation may be employed where the motive power is any gas under pressure, by properly designing 25 the engine for the particular motive power used.

My invention will best be understood by reference to the accompanying drawings showing a preferred embodiment thereof in 30 which—

Figure 1 shows the engine in plan view,

Fig. 2 shows the engine partly in front elevation and partly in vertical section through the engine crank shaft, taken along 35 the line 2—2 in Fig. 4,

Fig. 3 is a sectional view of the parts shown in Fig. 2 taken along the line 3—3,

Fig. 4 is a right hand end view of the parts shown in Fig. 2,

Fig. 5 is a view of the parts shown in 40 Fig. 2, taken along the line 5—5,

Fig. 6, is a sectional view of the parts shown in Fig. 3, taken along the line 6—6,

Fig. 7, is a top view of the dogs shown in 45 Fig. 6,

Fig. 8, is a sectional view of the parts shown in Fig. 7, taken along the line 8—8, and

Fig. 9 is a detail view of the casing clamp- 50 ing devices.

Similar numerals refer to similar parts throughout the several views.

As shown in Figs. 1 and 2, my engine consists of a casing 10, within which a rotor 55 11, rigidly secured to a shaft 12, is mounted.

Secured to the ends of the casing 10 and projecting upwardly therefrom are cylinders 13 and 14 containing pistons, 15 and 16 respectively. The pistons 15 and 16 are connected by piston rods 17 and 18 with cross-heads 19 and 20 supported on slides 21 and 22, said cross-heads being pivotally connected respectively with the upper ends of the connecting rods 23 and 24 which engage at their lower ends the cranks 25 and 26 carried by the shaft 12. Said cranks are oppositely disposed, so that the cycles of operation of the pistons 15 and 16 may be displaced a half rotation of the shaft 12 for a purpose to be described.

The cylinder 13 is provided with an intake port 27, and an exhaust valve 28. The shaft 12 has secured thereto a pinion 29 meshing with a gear 30 secured to a cam shaft 31, said pinion being of half the diameter of said gear to drive said cam shaft half as fast as the shaft 12. The shaft 31, has secured thereto cams 32 and 33 for operating the exhaust valves 28 and 34 of the cylinders 13 and 14 respectively. As shown in Fig. 5, 70 the valve 34 is connected to one end of a bell-crank lever 35, pivotally mounted at 36 on a stud projecting from the casing 10. The other end of said lever carries a roller 37 engaging the surface of the cam 33 as a result of which the valve 34 is opened during alternate down strokes of the piston 16. The cam 33 has projecting therefrom a pin 38 for engaging a contact spring 39 to move it into engagement with a second contact 75 spring 40 at substantially the beginning of alternate upstrokes of the piston 16, these contact springs being connected by conductors as indicated in the ignition circuit leading to the spark plug 41, as a result of which 80 the charges are fired in the cylinder 14 at the proper time.

Similar mechanism to that shown in Fig. 5 is provided for operating the exhaust valve 28 and controlling the firing of the 100 charges in the cylinder 13 from the cam 32, the only difference being that the cam 32 is displaced 90 degrees angularly from the cam 33 on the shaft 31 as a result of which the cycle of operation of the cylinder 13 is 105 displaced a half rotation of the shaft 12 from the cycle of operation of the cylinder 14.

As shown in Fig. 4, the cylinder 14 has 110 extending outwardly from its lower end,

beyond its intake port 42, a firing chamber 43 containing the spark plug 41 and this chamber communicates through the intake valve 44 with an intake compartment 45, 5 which in turn is connected by a pipe 46 with a suitable source of fuel not shown, as for example a carburetor. A similar construction is provided for supplying fuel to the intake port 27 of the cylinder 13.

10 As shown in Figs. 2 and 3, the rotor 11, which is cylindrical in form and closely fits the cylindrical bore of the casing 10, is provided with oppositely disposed annular recesses 47 and 48, into each of which the dogs 15 49 and 49^a drop when it is rotated into the upper part of the casing 10. As shown in Fig. 2, the recess 47 is provided with right hand and left hand end flanges 50 and 51 and the recess 48 is provided with similar 20 right hand and left hand end flanges 52 and 53, the dogs 49, 49^a being made of a combined width to fit closely against the inner surfaces of said flanges. The lower end of the cylinder 13 is provided with a downwardly extending passageway 54 terminating in an intake port 55 through the upper portion of the left hand end wall of the casing 10, which port opens against the outer surface of the one of the left hand 30 flanges 51 and 53 which happens to be uppermost. The cylinder 14 is provided with a similar passageway 56 terminating in an intake port 57 which opens against the outer surface of the one of the right hand flanges 35 50 and 52 which happens to be uppermost.

The leading portion of the flange 51, for the direction of rotation of the rotor indicated in Fig. 3, has formed therethrough one or more intake ports 58 and the trailing 40 portion of said flange has formed therethrough a scavenging port 59. Each of the ports 58 is a size to be somewhat more than completely covered by the edge of the adjacent dog 49. The port 55 in the casing is 45 disposed in advance of the free end of the dog 49 and registers with the ports 58 as they pass it, and the firing in the cylinder 13 is timed to occur just after the port 55 registers with the first one of the ports 58. 50 As a result, the fuel mixture compressed in the cylinder 13 by a down stroke of the piston 15 is admitted to the recess 47 between its leading end and the dogs 49 and 49^a and the firing which immediately follows 55 moves the piston 15 upward and turns the rotor 11 in the direction indicated by the arrow. An exhaust port 60 is formed through the end wall of the casing 10 in a position to register with the first one of the 60 ports 58 at the end of the power stroke and this together with the opening of the exhaust valve 28 dissipates the pressure on the spent gases in both the recess 47 and the cylinder 13. A scavenging port 61 is formed 65 through the end wall of the casing 10 to

register with the port 59 as soon as the dogs 49 and 49^a again enter the recess 47 and said port 61 is in the form of a curved slot extending upward and terminating at an angular position just behind the dog 49. 70 This results in sweeping the spent gases from the recess 47 as it rotates under the dogs 49, 49^a.

The flange 52 of the recess 48 is provided with intake and scavenging ports and the 75 end wall of the casing 10 adjacent to said flange is provided with intake, exhaust, and scavenging ports similar to those above described and performing the same functions for the cylinder 14 and recess 48. 80

As more clearly shown in Figs. 6, 7, and 8, the dogs 49, 49^a are mounted on a round rod 62 in a clearance compartment 63 projecting upwardly from the casing 10. Said dogs are secured to said rod by pins 64 and 65 rigidly carried by said rod and passing through clearance slots 66 and 67 in said dogs which permit a slight movement longitudinally of said dogs on said rod. The inner edge of the dog 49 has formed thereon 90 a tongue 68 extending from the rod 62 to the free end of said dog which enters with a sliding fit, a groove 69 formed in the adjacent edge of the dog 49^a. The rear portions of the dogs 49, 49^a are cylindrical and, as 95 indicated in Fig. 3, closely fit the casing at said portions. The adjacent ends of said cylindrical portions are dove-tailed together with a sliding fit as indicated at 70 in Fig. 6. The dogs are held in slightly separated 100 relation to bring their outer edges into engagement with the inner surface of the compartment 63 and of the rotor flanges, by a pointed set screw 71 extending through the top of said compartment, the point of said 105 screw resting between the adjacent edges of said cylindrical portions, but not tightly enough to prevent said dogs turning to enter and leave the recesses in the rotor.

The rod 62 has collars 72 secured adjustably by set screws to its ends for engaging the outer ends of springs 73 encircling said rod 62 and having their inner ends in engagement with lugs 74 projecting outwardly from the casing 10. Said springs serve to 110 hold said dogs in working position and to move the same quickly to said position as rotation of the rotor brings said recesses successively under said dogs. Said tongue and groove and dove-tail construction serve 115 to prevent leakage of the gases under pressure between said dogs.

It will be observed by reference to Fig. 3 that the rotor recess that is operative during a power stroke of either piston, is in the 120 upper right hand part of the casing 10 as viewed in Fig. 3, and that, therefore it is important that the adjacent engaging surfaces of the rotor and casing shall fit as closely as possible without undue friction. 130

To maintain this condition, and provide for the nicety of adjustment required, I place bearing blocks 75 on the shaft 12, one adjacent each end of the casing 10, held in place 5 by adjusting screws 76 extending in the desired lines of thrust, through arms 77 projecting from and rigidly secured to the casing, as shown in Fig. 5.

The engine above described is of the four 10 stroke or four cycle type; that is to say a complete cycle of operation of the cylinder 13 for example consists of first an upstroke drawing in a fuel charge, second, a downstroke compressing said charge, third an 15 upstroke during the firing of said charge and fourth, a downstroke exhausting the gases of combustion. The timing is such that during the same interval, the corresponding steps of the cycle of operation of 20 the cylinder 14 are first exhaust, second intake, third compression and fourth firing. In other words the cycles of operation of the two cylinders 13 and 14 are displaced from each other a half rotation of the 25 shaft 12.

To provide a good fit between the rotor 11 and the casing 10, I find it desirable to split the casing on the side opposite to the working position of the recesses 47 and 48. 30 During the construction of the casing, the split portions are held apart somewhat by suitable means during the boring of said casing, as a result of which the spring of the casing tends to move its cylindrical inner surface tightly against the rotor. To prevent too tight a fit in operation, the split parts are held apart by a shouldered screw 78 as indicated in Fig. 9, which screw provides by its adjustment a means for 35 permitting the parts to come together as the surfaces of the casing and rotor wear away. A jam nut 79 holds the screw 78 in any desired adjustment. The screw 78 is in 40 threaded engagement with a lug 80 projecting from the casing on one side of the split in the casing and its shouldered end exerts a thrust on the inner surface of a lug 81 projecting outwardly from the casing on the other side of the split. From 45 the shouldered portion of the screw 78 a threaded portion 82 of smaller diameter extends through a clearance hole in the lug 81, which is clamped against said shoulder by a nut on the portion 82. The casing is 50 preferably provided with a water jacket 83, operated in a manner usual with such devices, for preventing overheating of the rotary portion of the engine. The cylinders 13 and 14 may be similarly cooled if de- 55 sired.

While I have shown my invention in the particular embodiment above described, it will be understood that I do not limit myself to this exact construction as I may 60 employ equivalents known to the art at the

time of the filing of this application without departing from the scope of the appended claims.

What I claim is:

1. In an engine, the combination of a reciprocating portion and a rotary portion, said reciprocating portion comprising two cylinders, a piston in each cylinder, and a crank shaft connected with said pistons, said rotary portion comprising a casing secured 70 to said cylinders, a rotor having power recesses and rotatably mounted in said casing, a movable partition carried by said casing for successively entering said recesses to form a non-rotary wall thereof, passageways 75 in said casing extending from said cylinders to said rotor, and means for alternately establishing communication between said passageways and said recesses in front of said partition as they are engaged thereby. 80

2. In an engine, the combination of a reciprocating portion and a rotary portion, said reciprocating portion comprising two cylinders, a piston in each cylinder, and a crank shaft connected with said pistons, said rotary portion comprising a casing secured 90 to said cylinders, a rotor having power recesses and rotatably mounted in said casing, a movable partition carried by said casing for successively entering said recesses to form a non-rotary wall thereof, passageways 95 in said casing extending from said cylinders to said rotor, said cylinders being adjacent opposite ends of said rotor on the same side of said crank shaft, and flanges on said rotor at the ends of said recesses, said flanges having intake ports there-through in alternate arrangement for alternately establishing communication between 100 said passageways and said recesses in front of said partition as they are engaged thereby. 105

3. In an engine, the combination of a reciprocating portion and a rotary portion, 110 said reciprocating portion comprising two cylinders, a piston in each cylinder, and a crank shaft connected with said pistons, said rotary portion comprising a casing secured to said cylinders, a rotor having power recesses and rotatably mounted in said casing, a movable partition carried by said casing for successively entering said recesses to form a non-rotary wall thereof, passageways 115 in said casing extending from said cylinders to said rotor, means for alternately establishing communication between said passageways and said recesses in front of said partition as they are engaged thereby, said partition comprising two dogs, a rod secured 120 to said dogs and projecting through said casing, and a spring between said rod and casing tending to move said dogs into said recesses. 125

4. In an engine, the combination of a re- 130

5 ciprocating portion and a rotary portion, said reciprocating portion comprising two cylinders, a piston in each cylinder, and a crank shaft connected with said pistons, 5 said rotary portion comprising a casing secured to said cylinders, a rotor having power recesses and rotatably mounted in said casing, a movable partition carried by said casing for successively entering said 10 recesses to form a non-rotary wall thereof, passageways in said casing extending from said cylinders to said rotor, means for alternately establishing communication between said passageways and said recesses 15 in front of said partition as they are engaged thereby, said partition comprising two dogs, a rod secured to said dogs and projecting through said casing, a spring between said rod and casing tending to move 20 said dogs into said recesses, said dogs having interlocking portions on their adjacent ends preventing leakage between them and permitting motion of said dogs toward and from each other, and means for holding 25 said dogs away from each other to closely engage said casing and rotor at their outer ends. 85

5. In an engine, the combination of a reciprocating portion and a rotary portion, 30 said reciprocating portion comprising two cylinders, a piston in each cylinder, and a crank shaft connected with said pistons, said rotary portion comprising a casing secured to said cylinders, a rotor having power recesses and rotatably mounted in 35 said casing, a movable partition carried by said casing for successively entering said recesses to form a non-rotary wall thereof, passageways in said casing extending from 40 said cylinders to said rotor, said cylinders being adjacent opposite ends of said rotor on the same side of said crank shaft, flanges on said rotor at the ends of said recesses, said flanges having intake ports there- 45 through in alternate arrangement for alternately establishing communication between said passageways and said recesses in front of said partition as they are engaged thereby, said partition comprising two dogs, a 50 rod secured to said dogs and projecting through said casing, and a spring between said rod and casing tending to move said dogs into said recesses. 105

6. In an engine, the combination of a reciprocating portion and a rotary portion, 55 said reciprocating portion comprising two cylinders, a piston in each cylinder, and a crank shaft connected with said pistons, said rotary portion comprising a casing secured to said cylinders, a rotor having power recesses and rotatably mounted in 60 said casing, a movable partition carried by said casing for successively entering said recesses to form a non-rotary wall thereof, passageways in said casing extending from 65 110 115 120 125 130

said cylinders to said rotor, said cylinders being adjacent opposite ends of said rotor on the same side of said crank shaft, flanges on said rotor at the ends of said recesses, said flanges having intake ports there- 70 through in alternate arrangement for alternately establishing communication between said passageways and said recesses in front of said partition as they are engaged thereby, said partition comprising two dogs, a rod secured to said dogs and projecting through said casing, a spring between said rod and casing tending to move said dogs into said recesses, said dogs having interlocking portions on their adjacent ends preventing leakage between them and permitting motion of said dogs toward and from each other, and means for holding said dogs away from each other to closely engage said casing and rotor at their outer ends. 80 85

7. In an engine, the combination of a reciprocating portion and a rotary portion, said reciprocating portion comprising two cylinders, a piston in each cylinder, and a crank shaft connected with said pistons, 90 said rotary portion comprising a casing secured to said cylinders, a rotor having power recesses and rotatably mounted in said casing, a movable partition carried by said casing for successively entering said 95 recesses to form a non-rotary wall thereof, passageways in said casing extending from said cylinders to said rotor, means for alternately establishing communication between said passageways and said recesses in front 100 of said partition as they are engaged thereby, said casing being split on one side, and devices for holding said split portion in desired position to secure a sliding fit of said rotor in said casing. 105

8. In an engine, the combination of a reciprocating portion and a rotary portion, said reciprocating portion comprising two cylinders, a piston in each cylinder, and a crank shaft connected with said pistons, 110 said rotary portion comprising a casing secured to said cylinders, a rotor having power recesses and rotatably mounted in said casing, a movable partition carried by said casing for successively entering said recesses to form a non-rotary wall thereof, passageways in said casing extending from said cylinders to said rotor, means for alternately establishing communication between said passageways and said recesses in front 115 of said partition as they are engaged thereby, said rotor being secured to said crank shaft, bearings for said shaft carried by and movable relatively to said casing, and devices for moving and holding said bearings to secure a close fit between the operating 120 125 130 portions of said rotor and casing.

9. In an engine, the combination of a reciprocating portion and a rotary portion, said reciprocating portion comprising two

cylinders, a piston in each cylinder, and a crank shaft connected with said pistons, said rotary portion comprising a casing secured to said cylinders, a rotor having power recesses and rotatably mounted in said casing, a movable partition carried by said casing for successively entering said recesses to form a non-rotary wall thereof, passageways in said casing extending from said cylinders to said rotor, said cylinders being adjacent opposite ends of said rotor on the same side of said crank shaft, flanges on said rotor at the ends of said recesses, said flanges having intake ports therethrough in alternate arrangement for alternately establishing communication between said passageways and said recesses in front of said partition as they are engaged thereby, said casing being split on one side, and devices for holding said split portion in desired position to secure a sliding fit of said rotor in said casing.

12. In an engine, the combination of a reciprocating portion and a rotary portion, said reciprocating portion comprising two cylinders, a piston in each cylinder, and a crank shaft connected with said pistons, said rotary portion comprising a casing secured to said cylinders, a rotor having power recesses and rotatably mounted in said casing, a movable partition carried by said casing for successively entering said recesses to form a non-rotary wall thereof, passageways in said casing extending from said cylinders to said rotor, means for alternately establishing communication between said

10. In an engine, the combination of a reciprocating portion and a rotary portion, 25 said reciprocating portion comprising two cylinders, a piston in each cylinder, and a crank shaft connected with said pistons, said rotary portion comprising a casing secured to said cylinders, a rotor having power recesses and rotatably mounted in said casing, 30 a movable partition carried by said casing for successively entering said recesses to form a non-rotary wall thereof, passageways in said casing extending from said cylinders 35 to said rotor, said cylinders being adjacent opposite ends of said rotor on the same side of said crank shaft, flanges on said rotor at the ends of said recesses, said flanges having intake ports therethrough in alternate arrangement for alternately establishing communication between said passageways and 40 said recesses in front of said partition as they are engaged thereby, said rotor being secured to said crank shaft, bearings for said shaft carried by and movable relatively to said casing, and devices for moving and holding said bearings to secure a close fit between the operating portions of said rotor and casing.

13. In an engine, the combination of a reciprocating portion and a rotary portion, 45 said reciprocating portion comprising two cylinders, a piston in each cylinder, and a crank shaft connected with said pistons, said rotary portion comprising a casing secured to said cylinders, a rotor having power recesses and rotatably mounted in said casing, 50 a movable partition carried by said casing for successively entering said recesses to form a non-rotary wall thereof, passageways in said casing extending from said cylinders to said rotor, said cylinders being adjacent opposite ends of said rotor on the same side of said crank shaft, flanges 55

50 11. In an engine, the combination of a reciprocating portion and a rotary portion, said reciprocating portion comprising two cylinders, a piston in each cylinder, and a crank shaft connected with said pistons, said 115
55 rotary portion comprising a casing secured to said cylinders, a rotor having power recesses and rotatably mounted in said casing, a movable partition carried by said casing for successively entering said recesses to 120
60 form a non-rotary wall thereof, passageways in said casing extending from said cylinders to said rotor, means for alternately establishing communication between said passageways and said recesses in front 125
65 of said partition as they are engaged there-
on said rotor at the ends of said recesses, said flanges having intake ports there-through in alternate arrangement for alternately establishing communication between said passageways and said recesses in front of said partition as they are engaged thereby, said casing being split on one side, devices for holding said split portion in desired position to secure a sliding fit of said rotor in said casing, said rotor being secured to said crank shaft, bearings for said shaft carried by and movable relatively to said casing, and devices for moving and holding said bearings to secure a close fit between the operating portions of said rotor and casing. 130

14. In an engine, the combination of a reciprocating portion and a rotary portion, said reciprocating portion comprising two cylinders, a piston in each cylinder, and a crank shaft connected with said pistons, said rotary portion comprising a casing secured to said cylinders, a rotor having power recesses and rotatably mounted in said casing, a movable partition carried by said casing for successively entering said recesses to form a non-rotary wall thereof, passageways in said casing extending from said cylinders to said rotor, means for alternately establishing communication between 10 said passageways and said recesses in front of said partition as they are engaged thereby, said partition comprising two dogs, a rod secured to said dogs and projecting through said casing, a spring between said 20 rod and casing tending to move said dogs into said recesses, said casing being split on one side, devices for holding said split portion in desired position to secure a sliding fit of said rotor in said casing, said rotor being secured to said crank shaft, bearings 25 for said shaft carried by and movable relatively to said casing, and devices for moving and holding said bearings to secure a close fit between the operating portions of said 30 rotor and casing.

15. In an engine, the combination of a reciprocating portion and a rotary portion, said reciprocating portion comprising two cylinders, a piston in each cylinder, and a crank shaft connected with said pistons, said rotary portion comprising a casing secured to said cylinders, a rotor having power recesses and rotatably mounted in said casing, a movable partition carried by said casing for successively entering said recesses to form a non-rotary wall thereof, means for alternately subjecting said pistons to gas under pressure, and means for communicating the gas under pressure alternately to 45 said recesses in front of said partition.

16. In an engine, the combination of a casing, a rotor having power recesses and rotatably mounted in said casing, a movable partition carried by said casing for successively entering said recesses to form a non-rotary wall thereof, two sources of gas under pressure, and means for alternately connecting said sources with said recesses in front of said partition.

17. In an engine, the combination of a casing, a rotor having power recesses and rotatably mounted in said casing, a movable partition carried by said casing for successively entering said recesses to form a non-rotary wall thereof, said casing having intake ports in its ends, and flanges on said rotor at the ends of said recesses, said flanges having ports therethrough in alternate arrangement for alternately establishing communication 60 between said intake ports and said recesses in front of said partition, said partition comprising two dogs, a rod secured to said dogs and projecting through said casing, a spring

munication between said intake ports and 65 said recesses in front of said partition.

18. In an engine, the combination of a casing, a rotor having power recesses and rotatably mounted in said casing, a movable partition carried by said casing for successively 70 entering said recesses to form a non-rotary wall thereof, means for communicating gas under pressure successively to said recesses in front of said partition, said partition comprising two dogs, a rod secured to said 75 dogs and projecting through said casing, and a spring between said rod and casing tending to move said dogs into said recesses.

19. In an engine, the combination of a 80 casing, a rotor having power recesses and rotatably mounted in said casing, a movable partition carried by said casing for successively entering said recesses to form a non-rotary wall thereof, means for communicating 85 gas under pressure successively to said recesses in front of said partition, said partition comprising two dogs, a rod secured to said dogs and projecting through said casing, a spring between said rod and casing 90 tending to move said dogs into said recesses, said dogs having interlocking portions on their adjacent ends preventing leakage between them and permitting motion of said dogs toward and from each other, and means 95 for holding said dogs away from each other to closely engage said casing and rotor at their outer ends.

20. In an engine, the combination of a casing, a rotor having power recesses and rotatably mounted in said casing, a movable partition carried by said casing for successively 100 entering said recesses to form a non-rotary wall thereof, said casing having intake ports in its ends, flanges on said rotor at the ends 105 of said recesses, said flanges having ports therethrough in alternate arrangement for alternately establishing communication between said intake ports and said recesses in front of said partition, said partition comprising two dogs, a rod secured to said dogs and projecting through said casing, and a spring between said rod and casing tending 110 to move said dogs into said recesses.

21. In an engine, the combination of a casing, a rotor having power recesses and rotatably mounted in said casing, a movable partition carried by said casing for successively 115 entering said recesses to form a non-rotary wall thereof, said casing having intake ports 120 in its ends, flanges on said rotor at the ends of said recesses, said flanges having ports therethrough in alternate arrangement for alternately establishing communication between said intake ports and said recesses in 125 front of said partition, said partition comprising two dogs, a rod secured to said dogs and projecting through said casing, a spring

- between said rod and casing tending to move said dogs into said recesses, said dogs having interlocking portions on their adjacent ends preventing leakage between them and 5 permitting motion of said dogs toward and from each other, and means for holding said dogs away from each other to closely engage said casing and rotor at their outer ends.
- 10 22. In an engine, the combination of a casing, a rotor having power recesses and rotatably mounted in said casing, a movable partition carried by said casing for successively entering said recesses to form a non-rotary 15 wall thereof, two sources of gas under pressure, and means for alternately connecting said sources with said recesses in front of said partition, said casing being split on one side, and devices for holding said split 20 portion in desired position to secure a sliding fit of said rotor in said casing.
23. In an engine, the combination of a casing, a rotor having power recesses and rotatably mounted in said casing, a movable partition carried by said casing for successively entering said recesses to form a non-rotary 25 wall thereof, two sources of gas under pressure, and means for alternately connecting said sources with said recesses in front of said partition, said rotor being secured to a shaft, bearings for said shaft carried by and movable relatively to said casing, and devices for moving and holding said bearings to secure a close fit between the operating 30 portions of said rotor and casing.
24. In an engine, the combination of a casing, a rotor having power recesses and rotatably mounted in said casing, a movable partition carried by said casing for successively 35 entering said recesses to form a non-rotary wall thereof, said casing having intake ports in its ends, flanges on said rotor at the ends of said recesses, said flanges having ports therethrough in alternate arrangement for 40 alternately establishing communication between said intake ports and said recesses in front of said partition, said casing being split on one side, and devices for holding 45 said split portion in desired position to secure a sliding fit of said rotor in said casing.
25. In an engine, the combination of a casing, a rotor having power recesses and rotatably mounted in said casing, a movable 50 partition carried by said casing for successively entering said recesses to form a non-rotary wall thereof, said casing having intake ports in its ends, flanges on said rotor at the ends of said recesses, said flanges having 55 ports therethrough in alternate arrangement for alternately establishing communication between said intake ports and said recesses in front of said partition, said casing being split on one side, devices for holding 60 said split portion in desired position to secure a sliding fit of said rotor in said casing, said rotor being secured to a shaft, bearings for said shaft carried by and movable relatively to said casing, and devices for moving and holding said bearings to secure a close fit between the operating portions of said rotor and casing.
26. In an engine, the combination of a 65 casing, a rotor having power recesses and rotatably mounted in said casing, a movable partition carried by said casing for successively entering said recesses to form a non-rotary wall thereof, means for communicating gas under pressure successively to said recesses in front of said partition, said partition comprising two dogs, a rod secured to said dogs and projecting through said casing, a spring between said rod and casing tending to move said dogs into said recesses, said casing being split on one side, and devices for holding said split portion in desired position to secure a sliding fit of 70 said rotor in said casing.
27. In an engine, the combination of a 75 casing, a rotor having power recesses and rotatably mounted in said casing, a movable partition carried by said casing for successively entering said recesses to form a non-rotary wall thereof, means for communicating gas under pressure successively to said recesses in front of said partition, said partition comprising two dogs, a rod secured to said dogs and projecting through said 80 casing, a spring between said rod and casing tending to move said dogs into said recesses, said rotor being secured to a shaft, bearings for said shaft carried by and movable relatively to said casing, and devices for moving and holding said bearings to secure a close fit between the operating portions of said 85 rotor and casing.
28. In an engine, the combination of a 90 casing, a rotor having power recesses and rotatably mounted in said casing, a movable partition carried by said casing for successively entering said recesses to form a non-rotary wall thereof, said casing having intake ports in its ends, flanges on said rotor at the ends of said recesses, said flanges having 95 ports therethrough in alternate arrangement for alternately establishing communication between said intake ports and said recesses in front of said partition, said casing being split on one side, devices for holding 100 said split portion in desired position to secure a sliding fit of said rotor in said casing, said rotor being secured to a shaft, bearings for said shaft carried by and movable relatively to said casing, and devices for moving and holding said bearings to secure a close fit between the operating portions of said 105 rotor and casing.
29. In an engine, the combination of a 110 casing, a rotor having power recesses and rotatably mounted in said casing, a movable partition carried by said casing for successively entering said recesses to form a non-rotary wall thereof, said casing having intake ports in its ends, flanges on said rotor at the ends of said recesses, said flanges having 115 ports therethrough in alternate arrangement for alternately establishing communication between said intake ports and said recesses in front of said partition, said casing being split on one side, devices for holding said split portion in desired position to secure a sliding fit of said rotor in said casing, said rotor being secured to a shaft, bearings for said shaft carried by and movable relatively to said casing, and devices for moving and holding said bearings to secure a close fit between the operating portions of said rotor and casing.
30. In an engine, the combination of a 120 casing, a rotor having power recesses and rotatably mounted in said casing, a movable partition carried by said casing for successively entering said recesses to form a non-rotary wall thereof, said casing having intake ports in its ends, flanges on said rotor at the ends of said recesses, said flanges having 125 ports therethrough in alternate arrangement for alternately establishing communication between said intake ports and said recesses in front of said partition, said rotor being secured to a shaft, bearings for said shaft carried by and movable relatively to said casing, and devices for moving and holding said bearings to secure a close fit between the operating portions of said rotor and casing.

3
sively entering said recesses to form a non-
rotary wall thereof, means for communicat-
ing gas under pressure successively to said
recesses in front of said partition, said
partition comprising two dogs, a rod se-
cured to said dogs and projecting through
said casing, a spring between said rod and
casing tending to move said dogs into said
recesses, said casing being split on one side,
10 devices for holding said split portion in de-
sired position to secure a sliding fit of said

rotor in said casing, said rotor being secured
to a shaft, bearings for said shaft carried
by and movable relatively to said casing,
and devices for moving and holding said
bearings to secure a close fit between the
operating portions of said rotor and casing.

In witness whereof I hereunto subscribe
my name this 11th day of August, A. D.
1919.

ALLEN W. BODELL.
